UNITED STATES PATENT OFFICE

SAMUEL J. MOLLET, OF MASSILLON, OHIO

PRINTING CYLINDER

Original application filed February 28, 1929, Serial No. 343,523. Divided and this application filed June 27, 1930. Serial No. 464,157.

The present invention relates to a form cylinder for printing presses and more particularly to a cylinder having a form composed of flexible material adapted to be wrapped tightly upon the peripheral surface of the cylinder and to the means for detachably securing such a form to the cylinder.

The present application is a division of my copending application Serial No. 343,523, filed Feb. 28, 1929, for printing presses in which I have disclosed a printing press for printing large sheets such as used for printing roadside signs, the press being provided with large form and compression cylinders between which the sheet is fed in a straight line at a linear speed corresponding to the peripheral speed of the cylinders.

The present invention has for its object to provide a form which may be wrapped about a printing cylinder and which may be made to closely conform to the cylindrical surface, together with means by which the form may be quickly and easily applied to the cylinder and drawn into snug engagement with the surface of the cylinder throughout its periphery.

With the above and other objects in view, the invention may be said to comprise the device as illustrated in the accompanying drawings hereinafter described and particularly set forth in the appended claim, together with such variations and modifications thereof as will be apparent to one skilled in the art to which the invention appertains.

Reference should be had to the accompanying drawings forming a part of this specification in which:

Figure 1 is a vertical section through the printing cylinder showing operations of the compression cylinder and inking roller.

Fig. 2 is a section taken on the line indicated at 2-2 in Fig. 1.

Fig. 3 is a fragmentary vertical section on an enlarged scale through the recessed portion of the printing cylinder, showing the form tightening reel.

Fig. 4 is a fragmentary end elevation of the form tightening reel.

In the accompanying drawings, a portion 50 of the frame 1 of the machine is shown which

supports a printing cylinder 2, which is fixed to a transverse shaft 3 journaled at its ends in suitable bearing members mounted in the frame 1. The cylinder consists of a plurality of spaced spiders 4 fixed to the shaft, the spiders being preferably formed in two sections secured together by bolts 5, the peripheral wall of the cylinder being composed of wooden slats 6, which abut edge to edge and which are suitably secured at their ends to the rims of the spiders 4. At one point in the periphery of the cylinder, one or more slats are omitted to provide a gap or recess 7.

A form 8 is attached to the periphery of the cylinder and preferably consists of a sheet of flexible and elastic material such as rubber composition. A compression cylinder 9 is so mounted that its periphery engages the periphery of the printing cylinder and the compression cylinder is preferably of the same diameter as the printing cylinder and driven at the same peripheral speed, the compression cylinder being provided with a longitudinal recess 10 across its periphery, which registers with the recess 7 of the printing cylinder during rotation of the cylinders, as shown in Fig. 3.

The form 8 receives a coating of ink or paint from a suitable inking roller 11, which applies a uniform coating to the surface of the form. Discs 12 are fixed to the shaft 3 and gears 13 which mesh with similar gears on the shaft of the compression cylinder are secured to the discs 12 by means of bolts 14 which pass through arcuate slots 15 in the discs 12. By means of the bolt and slot connections, the gears 13 may be adjusted angularly with respect to the cylinder to insure proper registry of recessed portions of the two cylinders and to insure proper positioning of the form with respect to the sheets being printed on.

As shown in Fig. 3 of the drawings, the sheet to be printed is fed in a straight line between the cylinders by means of endless chains 16 which carry suitable grippers 17, which are so spaced on the endless chains that they are received in the recesses 10 of the compression cylinder during their passage be-

tween the cylinders. One end of the form 8 is secured in the recesses 7 so that this end of the form engages the end of the sheet as it is drawn between the cylinders, the form rolling on the surface of the sheet during its passage between the cylinders transfers a coating of ink or paint to the sign and prints the entire sign, which may be of a width and length corresponding to the width and length of the form.

10 As shown in Fig. 3, brackets 18 are attached to the rims of the spiders at opposite ends of the cylinder within the gap or recess 7, these brackets forming bearings for a shaft 19 which, between the brackets, is square in shape. The shaft 19 has an end 20 projecting outwardly through one of the brackets 18, the end of the shaft being squared to receive a suitable hand crank by which the shaft may 15 be rotated. The projecting end of the shaft has a ratchet 21 fixed thereto and this ratchet is engaged by a pawl 22 pivoted to the bracket 18. The form 8 is provided with a fabric back 23 which extends beyond one end of the 20 composition body of the form. The extending fabric end is wound upon the square shaft 19 which forms a reel for winding up the fabric and drawing the form tightly against the surface of the cylinder throughout 25 its periphery. The opposite end of the form is rigidly attached to the cylinder by suitable means such as nails 24 driven into the slat at one edge of the recess 7. The ratchet 21 and pawl 22 serve to lock the 30 shaft 19 against rotation in the direction to unwind the fabric so that the desired tension may be put upon the form by rotating the shaft in the direction to wind the fabric thereon and this tension will be maintained 35 during the operation of the press.

40 When it is desired to replace one form with another the pawl 22 may be lifted out of engagement with the ratchet and the shaft 19 turned until the fabric is released, whereupon 45 the form can be readily stripped from the cylinder. In applying a form to the cylinder, one end is rigidly secured to the cylinder and the projecting fabric at the opposite end is wound upon the reel until sufficient tension 50 is applied to the form to cause it to snugly engage the cylinder throughout its periphery.

55 The form 8 has cut away portions 25 in the form of the letters or characters of the sign to be printed and the entire surface of the form is coated with ink or paint by the roller 11, the coating being transferred to the surface of the sheet being printed, except on the portions thereof registered with the cut-away 60 portions 25 of the form.

65 It will be apparent that the present invention provides a very simple and convenient means of mounting a form upon the printing cylinder which holds a form securely in place and which permits one form to be

quickly and easily detached and replaced with another.

Furthermore, it is to be understood that the particular form of apparatus shown and described, and the particular procedure set forth, are presented for purposes of explanation and illustration and that various modifications of said apparatus and procedure can be made without departing from my invention as defined in the appended claim.

75

75

What I claim is:

A form cylinder comprising spaced spiders and a peripheral portion formed of contiguous longitudinal wooden slats attached at their ends to said spiders, said slats being spaced apart at one portion of the periphery to provide a longitudinal gap, brackets carried by said spiders centrally of the gap, a shaft journaled in said brackets, said shaft having a squared portion between said brackets and an end projecting outwardly from one of said brackets adapted to receive a crank for turning the shaft, a form composed of a flexible composition body and a fabric backing, one end of which projects beyond the body and is adapted to be wound on the square portion of said shaft, the opposite end of the form being secured to the cylinder, and means for releasably locking said shaft against turning movement in a direction to unwind the fabric backing.
